(57) **CLAIM**

The ornamental design for a heel wrap, as shown and described.

DESCRIPTION

FIG. 1 is a perspective view of a heel wrap showing my new design;

FIG. 2 is a first side elevational view thereof;

FIG. 3 is an opposite side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines in FIGS. 1-7 represent portions of the footwear that form no part of the claimed design.
